HYDRAULIC PRESSURE BOOSTER

Martin B. Conrad, Downey, Calif., assignor to
Baker Oil Tools, Inc., Los Angeles, Calif., a cor-
poration of California

Application April 25, 1952, Serial No. 284,345

18 Claims. (Cl. 103—52)

1 The present invention relates to apparatus for increasing the pressure of fluid delivered to the apparatus from another source.

An object of the present invention is to provide an improved apparatus which utilizes fluid under pressure to increase or boost the pressure of such fluid to very high values.

Another object of the invention is to provide an apparatus which can be manipulated selectively to obtain increase in the pressure of fluid or allow the fluid to pass through the apparatus without increase in its pressure.

A further object of the invention is to provide an apparatus for increasing fluid pressure, which can be easily shifted between different relative positions, despite the presence of high pressures, to effect an increase in the fluid pressure supplied to the apparatus or to effect no increase in such fluid pressure.

Still another object of the invention is to provide a hydraulic pressure booster embodying seal rings to prevent leakage from the apparatus or between its various parts, and in which the pressure differential across the seal rings is considerably decreased, in order to avoid subjecting such rings to excessive hydraulic forces.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

Figure 1 is a side elevation, on a reduced scale, of an apparatus embodying the invention, with a small portion broken away to provide a sectional view;

Fig. 2 is an enlarged longitudinal section of the hydraulic booster apparatus, with the parts arranged in position to effect no increase in the pressure of the fluid passing through the apparatus;

Fig. 3 is a view similar to Fig. 2, with the apparatus positioned to effect a boosting or increase in the pressure of the fluid supplied to the apparatus;

Fig. 4 is a cross-section taken along the line 4—4 on Fig. 3;

Fig. 5 is a fragmentary longitudinal section, 55

2 on an enlarged scale, through the check valve portion of the apparatus.

The specific embodiment of the invention illustrated in the drawings has been particularly designed for providing fluid under exceedingly high pressures, for the purpose of testing articles, or other devices. It is to be understood, however, that the apparatus is capable of more general use than has just been indicated. As an example, it can also be used for pressure actuating purposes in general, in which an increase in the hydraulic pressure over that supplied by some other pressure source, such as a pump, is required.

As disclosed in the drawings, the hydraulic booster device includes a main body 10 that is generally elongate, and which may comprise several sections, in order to facilitate appropriate assembly of the apparatus. Thus, the main body includes a rearward section 11 terminating in an enlarged head 12 carrying a forwardly facing cam surface 13 for cooperation with a companion face or axial cam surface 14 formed on the rearward end of a cylinder 15. This cylinder is slidable longitudinally with respect to the body 10 in effecting selective shifting of the apparatus to a position in which it will merely allow fluid under pressure to pass through the apparatus, without increasing its pressure, to one in which the apparatus is operable to effect a substantial boost or increase in the pressure of the fluid supplied to it. The rearward body section 12 is threaded into a forward body member 16, which, in turn, is threaded onto a nipple 17 that can be screwed into an outlet or discharge pipe 18. A suitable inlet pipe 19 is threaded into the body head 12 at the rearward portion of the apparatus.

The cylinder 15 may be considered as having a slide valve portion 20, and also a fluid motor and pump portion 21 which is effective when the pressure of the fluid delivered to the apparatus is to be increased. The slide valve portion 20 is provided in the rearward section of the cylinder, and includes an internal groove or valve chamber 22 adapted to cooperate with inlet and outlet ports 23, 24 in the body section. Fluid passes from the inlet pipe 19 through an inlet passage 25 in the body and into the inlet port 23. When the valve chamber 22 subtends the inlet port 23 and the body outlet port 24, as shown in Fig. 2, the fluid can pass into the chamber or groove 22 and through the outlet port 24 into an outlet passage 26 extending through the rear body section 11, this outlet passage 26 having no direct communication with the inlet passage 25. From

the outlet passage 26, the fluid under pressure can displace a suitable check valve 27 and continue its flow through the nipple passage 28 and on into the outlet pipe 18.

As disclosed in the drawings, and particularly Fig. 5, the check valve 27 includes a seat 29 provided by the forward end of the body section 11, which is engaged by a valve head 30 centered with respect to the seat by a rearwardly projecting conical axial portion 31. A helical compression spring 32 bears against the head 30 and against a spring seat 33 in the rearward portion of the nipple 17, urging the head 30 constantly against its companion seat 29. Leakage between the seat 29 and head 30 is prevented by providing a suitable seal ring or gasket 34, which may take the form of a rubber O ring, in an annular groove 35 in the head 30 and bearing against the seat 29. The fluid under pressure can shift the valve head 30 forwardly from its seat 29 against the action of the spring 32, but any tendency for such fluid to flow reversely back into the outlet passage 26 is precluded by engagement of the head 30 and its seal ring 34 with the seat 29.

Leakage of fluid from the slide valve chamber 22 is prevented by a suitable seal on each side of the chamber. As illustrated in the drawings, a pair of rubber O rings 36, 37 is mounted in suitable internal grooves 38, 39 in the cylinder 15 and slidably seal against the periphery of the rearward body portion 11. When the cylinder 15 is in the position disclosed in Fig. 2, it is quite apparent that fluid under pressure can flow between the inlet and outlet ports 23, 24, and cannot leak longitudinally in either longitudinal direction between the valve chamber and body portion 11. When the cylinder 15 has been shifted, as described hereinafter, to the position illustrated in Fig. 3, the seal rings 36, 37 on opposite sides of the chamber 22 will be disposed on opposite sides of the outlet port 24, and will prevent flow of fluid from the outlet port 24 to the inlet port 23, and also leakage of fluid through the valve chamber to the exterior of the latter.

The forward body section 16 has an outside diameter substantially less than the inside diameter of the sleeve or pump and motor portion 21 of the cylinder, which extends forwardly from the cylinder head or slide valve portion 20 that contains the valve chamber 22 and seal rings 36, 37. Such difference in diameter provides an annular space 40 through which the annular skirt 41 of a piston 42 may slide, this piston having a rearward piston head 43 which is slidable within the annular cylinder space 44 that is defined between the interior of the cylinder sleeve 21 and the external periphery of the rearward body member 11. Leakage between the exterior of the piston 42 and the cylinder skirt 21 is prevented by providing a suitable seal ring 45, such as a rubber O ring, in an internal groove 46 in the sleeve 21, which slidably bears upon the periphery of the piston skirt 41. Leakage between the inner surface of the piston skirt 41 and the forward body portion 16 is prevented by providing a plurality of seal rings 47, 48, such as rubber O rings, in longitudinally spaced grooves 49, 50 in the forward body section 16, which slidably engage the inner surface of the piston skirt. Thread seals are also provided to prevent leakage of fluid through the threaded joint 51 between the forward and rearward body sections 16, 11. As disclosed, these thread seals 52, 53 may be rubber O rings, one of which 52 is disposed in an internal groove 54 in the forward body section 16.

and bearing against the periphery of the rearward body section 11 on one side of the threaded connection 51, the other O ring 53 being provided in an external groove 55 in the rearward body section 11 on the other side of the threaded joint 51 and bearing against the inner surface of the forward body portion 16.

A thread seal 56 is also provided between the nipple 17 and the forward body portion 16, consisting of a rubber O ring mounted in an external groove 57 in the nipple and engaging the inner surface of the forward body portion 16 rearwardly of its threaded connection 53 with the nipple 17.

15. Leakage between the piston head 43 and the rear body section 11 is prevented by providing a suitable seal ring 59, such as a rubber O ring, in an internal groove 60 in the piston head 43 which slidably bears upon the periphery of the body 11.

20. It is to be noted that the piston 42 separates the cylinder 15 and body 10 into two portions, one of which is a fluid motor portion 61 rearwardly of the piston head 43, and the other of 25 which is a fluid pump portion 62 forwardly of the piston head. There is an annular cylinder space 63 formed between the inner surface 64 of the piston skirt and the exterior 65 of the body portion 11, in which fluid may be contained, 30 fluid passing into this cylinder space 63 through a lateral port 66 adjacent the rearward end of the forward body portion 16 and extending between the cylinder space 63 and the outlet body passage 26.

35. Fluid under pressure can be supplied to the enlarged fluid motor cylinder space 67 from the inlet passage 25 and inlet port 23, when the cylinder 15 has been shifted to an appropriate position, such as the position illustrated in Fig. 3.

40. When disposed in this forward position, the valve seal rings 36, 37 are located on opposite sides of the outlet port 24. However, at this time, a booster passage 68 in the cylinder is placed in communication with the inlet port 23, this passage having a suitable transverse branch or port 69 alignable with the inlet port 23 and allowing fluid under pressure from such port to flow through the passage 68 and into the enlarged cylinder space 67 rearwardly of the piston 42. Leakage of fluid from this booster passage 68 and inlet port 69, when the cylinder has been 45 shifted forwardly to the position disclosed in Fig. 3, is prevented in a forward direction by the valve seal ring 36 engaging the body periphery. Leakage in a rearward direction is prevented by 50 engagement of a suitable seal ring 70, such as a rubber O ring, with the periphery of the body 11, the ring being contained in an internal groove 55 in the cylinder 15.

55. When the cylinder 15 occupies its rearward position on the body 10, as disclosed in Fig. 2, the fluid motor cylinder space 67 and booster passage 68 are then opened to the atmosphere, so that fluid can bleed from the cylinder space 67 60 and allow return movement of the piston 42, such return movement being limited by engagement of the piston with a transverse stop shoulder 72 provided on the body. The fluid in the motor cylinder space 67 can flow through the booster passage 68 and into an annular area 73 65 between the inner surface of the cylinder 15 and a reduced diameter portion 74 of the body 11, the fluid then passing out through a transverse bleeder port 75 in the cylinder member to the 70 atmosphere.

The cylinder 15 is shifted relative to the body 10 between the positions disclosed in Fig. 2 and Fig. 3 by a cam device under manual turning effort, that can be supplied by a suitable handle 76 extending transversely from the cylinder. This handle has a threaded inner end 77 screwed into a companion threaded bore 78 in the cylinder, leakage outwardly from the cylinder and around the handle being prevented by a suitable seal ring 79 in a groove 80 in the handle 76 engaging the inner surface of a counterbore 81 in the cylinder.

The cam device includes an axial cam 82 on the body head 12 facing in a forward direction, which is engageable by a companion cam 83 at the rear portion of the cylinder 15 and facing in a rearward direction. The body has a transverse cam surface 84, or face, which terminates in an inclined rise portion 85, that extends to a transverse cam surface or face 86 disposed forwardly of the other cam face 84. The high cam face 86 of the body engages a companion low cam face 87 on the cylinder 15, which extends to a rearwardly extending inclined cam rise face 88, companion to the other cam rise face 85, that terminates at a high cam face 89 on the cylinder, which, as disclosed in Fig. 1, is then adjacent the low transverse cam face 84 on the body. A pair of such diametrically opposite high, low and inclined cam faces 84—89 may be provided on the body 10 and also on the rearward portion of the cylinder 15.

It is apparent that when the cylinder has been turned to the position illustrated in Figs. 1 and 2, the cylinder 15 occupies the rearward position with respect to the body 10, which allows the fluid to pass through the apparatus without its pressure being increased. Upon rotating the cylinder 15 a partial revolution by grasping the handle 76, the coengaging inclined cam faces 85, 88 will cause the cylinder 15 to shift forwardly on the body 10 to a position in which the high cam faces 86, 89 are in engagement, which will locate the cylinder in the position with respect to the body illustrated in Fig. 3. The cylinder 15 can then be moved arcuately in the reverse direction, and the parts will return to their Figs. 1 and 2 positions. Such return motion is positive through the provision of a stop and return screw 90 that is threaded through the cylinder for reception within a helical groove 91 formed in the body 10 adjacent its head 12. This helical groove will have the same angle as the inclined cam surfaces 85, 88 that cause relative movement of the cylinder 15 in a forward direction.

When the cylinder 15 is located on the body 10 in the non-pressure boosting position shown in Figs. 1 and 2, the fluid will pass from the inlet pipe 19 into the inlet passage 25 and thence through the inlet port 23 into the valve chamber 22, continuing from the valve chamber through the outlet port 24 into the outlet passage 26, 60 shifting the valve head 30 off its seat 29, and continuing on out through the nipple passage 28 and the outlet pipe 18. Thus, the fluid under pressure in the inlet pipe 19, which may be supplied from any suitable source such as a pump (not shown), does not have its pressure increased in any particular.

Such fluid under pressure in the outlet passage 26 will pass into the pump cylinder space 63 through the transverse port 66, urging the piston 42 in a rearward direction and into engagement with its companion stop shoulder 72. This action is permitted since the fluid on the head end of the piston 42 can pass outwardly to atmosphere

through the booster passage 68 and bleeder port 75.

When it is desired to increase the pressure of the fluid that is now to be discharged from the apparatus, the handle 76 is grasped, and the cylinder 15 is rotated so that the cam surfaces 85, 88 shift the cylinder forwardly of the body 10 of the apparatus, and to the position disclosed in Fig. 3, in which the booster passage 68 and fluid motor cylinder space 67 are placed in communication with the inlet passage 25 and its port 23, the valve chamber 22 then merely extending over the outlet port 24, with the seal rings 36, 37 disposed on opposite sides of the latter. One of the valve chamber seal rings 36 and the rearward seal ring 70, located on opposite sides of the booster passage port 69, are also on opposite sides of the inlet port 23, to prevent leakage therefrom. The fluid under pressure in the inlet pipe 19 can then flow through the inlet passage 25 and port 23 into the booster passage 68, and into the enlarged cylinder space 67, urging the piston 42 in a forward direction within the cylinder 15 and causing it to force the fluid in its cylinder space 63 of smaller area through the transverse passage 66 and into the outlet passage 26, from which such fluid under pressure will be forced around the check valve 30 and into the nipple passage 28 and outlet pipe 18. The fluid can be discharged until the piston 42 has been shifted to its full extent forwardly, which is determined by engagement of the piston head 43 with the rearward end 92 of the forward body member 16.

When the cylinder and body parts 15, 10 are in the relative positions disclosed in Fig. 3, the pressure of the fluid in the smaller pump cylinder portion 63 is increased to a considerable extent over the pressure of the fluid supplied from the inlet pipe 19 to the fluid motor cylinder space 67. It is to be noted that the annular cross-sectional area R of this latter space 67 is much greater than the annular area S of the fluid pump cylinder space 63 measured between the inner surface 64 of the piston skirt and the periphery 65 of the body 11. As a matter of fact, the annular area R of the larger cylinder space 67 can be considerably greater than the annular area S of the fluid pump cylinder space 63.

As disclosed in the drawings, the annular area R is approximately twice the annular area S. If it is assumed, merely by way of example, that the pressure of the fluid in the inlet pipe 19 is 7,000 p. s. i., that will be the pressure of the fluid supplied to the fluid motor cylinder space 67. Since the area R is twice that of the area S, then the pressure of the fluid in the pump cylinder space 63, and the pressure of such fluid when it is being discharged into the outlet passage 26, and from the apparatus, will be 14,000 p. s. i., from which it is evident that a considerable boost or increase in the pressure has been accomplished hydraulically through use of the fluid pressure in the inlet pipe 19 itself. Of course, in obtaining such increase in pressure, it is first necessary to fill the cylinder space 63 in the pump portion of the apparatus, as well as the various passages 26, 66 communicating therewith, with fluid, and this can be done very readily when the parts are located in their non-boosting position shown in Figs. 1 and 2. Thereafter, the shifting of the cylinder 15 with respect to the body 10 to the position shown in Fig. 3 will enable the fluid under pressure in the inlet pipe 19 to effect a considerable boost or increase in the pressure of the fluid

in the pump cylinder portion 63 and the passages 66, 26 communicating therewith.

After the piston 43 has moved to its forward limit, to displace the fluid from the cylinder 63, the parts can again be shifted back to the position disclosed in Figs. 1 and 2, by grasping the handle 76 and rotating the cylinder 15 a partial revolution, the return screw 90 causing the cylinder to shift to such rearward position. When this occurs, the pressure in the inlet pipe 19 can then pass again through the inlet passage 25 and port 23 into the valve chamber 22, continuing through the outlet port 24 into the outlet passage 26, and then through the pump body port 66 into the pump cylinder 63, acting against the skirt side of the piston 43 to urge the latter to its full rearward position against the stop shoulder 72, as disclosed in Fig. 2.

In view of the comparatively high pressures to which the seal rings in the pump portion of the booster apparatus are subjected, it is desired to decrease the pressure drop across certain of these rings. In the example noted above, fluid at 7,000 p. s. i. is boosted to 14,000 p. s. i. During such boosting operation, the piston ring 59 is subjected to a 7,000 p. s. i. pressure at the head end of the cylinder 15 and to a 14,000 p. s. i. pressure in the pump cylinder 63 on its other side. Accordingly, there is a 7,000 p. s. i. pressure drop across this ring 59, which is not excessive, and which the ring can withstand safely. Similarly, the seal ring 45 between the cylinder skirt 21 and the piston skirt 41 is subjected to the 7,000 p. s. i. pressure in the fluid motor cylinder space 61, the pressure on the other side of this ring being atmospheric. Accordingly, there is only a 7,000 p. s. i. pressure drop across this ring, which it can safely withstand. However, the seal rings 41, 48 on the forward body portion 16 are subjected on one side to the high pressure, which has been assumed to be 14,000 p. s. i., the pressure on the other side of these seal rings ordinarily being atmospheric. Thus, the rings 41, 48 would be subjected to a 14,000 p. s. i. pressure differential, which might be excessive and which might cause displacement of some of the sealing ring material from the ring grooves 49, 50 in which they are located. Such excessive pressures are avoided in the present case, by an arrangement that will now be described.

The rearward body portion 11 has a passage 93 formed therein, opening into the cylinder space 61 of the fluid motor 61 adjacent the stop shoulder 72, and also opening into an annular space 94 between the forward and rearward body portions 16, 11, which communicates with a port 95 that extends to the periphery of the forward body portion 16 between the longitudinally spaced seal rings 41, 48. By virtue of this passage 93, the pressure in the motor cylinder space 61 is bled, or allowed to pass, to the clearance space between the forward body member 16 and the cylinder skirt 41 between the longitudinally spaced rings 41, 48. Assuming the pressure in the motor cylinder space 61 to be 7,000 p. s. i., then this same fluid pressure is imposed upon both of the longitudinally spaced rings 41, 48. Accordingly, the high pressure in the pump cylinder space of 14,000 p. s. i. on the rearward ring 41 is offset by the pressure of 7,000 p. s. i. on the other side of this ring, which means that the ring 41 is being subjected only to a pressure differential of 7,000 p. s. i. The other ring 48 has the pressure of 7,000 p. s. i. disposed on one side of it and atmospheric pressure on the other side.

Thus, the two rings 41, 48 are fully capable of withstanding such pressure differentials, which are considerably lower, namely only one-half in the example specifically given, than the pressure to which the ring 41 would otherwise have been subjected.

Similarly, the thread seal ring 52, which is subject to the high pressure in the pump cylinder space 63, will have the pressure differential across it decreased to the same extent as the outer ring 41, inasmuch as the fluid from the motor cylinder space 61 is capable of acting on its low pressure side. The other thread seal ring 53 has the 7,000 lb. pressure imposed on one side and 14,000 p. s. i. pressure imposed on its other side, because of the fact that such high pressure will be present in the valve chamber 97 between the rearward body member 11 and the threaded nipple 17. However, the pressure drop across this seal ring 53 is also only 7,000 p. s. i., which it can safely withstand.

It is, accordingly, apparent that a hydraulic booster apparatus has been provided, in which the fluid under pressure can be supplied to the apparatus, and such pressure then increased to a considerable extent by utilizing fluid under pressure from the same source. The apparatus may be manipulated to either allow the fluid under pressure from the source to pass through the apparatus, or to obtain a considerable increase in its pressure. Despite the output of comparatively high pressures, most of the seal rings of the apparatus are not subjected to such great pressure differentials, in view of the use of some of the inlet pressure to offset the final outlet pressure. The cylinder and valve portions are easily shifted, the cylinder being under a substantially balanced condition so far as the inlet fluid pressure is concerned when disposed in its non-boosting position shown in Fig. 2, which allows the cylinder 15 to be readily manipulated to shift it in a forward direction to its boosting position shown in Fig. 3. Return of the cylinder to its original position is also readily accomplished, inasmuch as any fluid under pressure within the motor cylinder space 61 will be effective in assisting return of the cylinder to its rearward non-boosting position. Despite the fact that such pressure forces are present when the cylinder is in the pressure boosting position, shown in Fig. 3, it still cannot shift to the rearward direction, in view of the engagement of the high cam faces 86, 89 with one another, these faces being disposed in planes that are at right angles to the axis of the apparatus.

The inventor claims:

1. Hydraulic pressure booster apparatus, comprising a fluid motor, a fluid pump operatively connected to said motor to be actuated thereby, means providing an inlet for fluid to be supplied to said fluid motor and fluid pump, first passage means for conducting fluid from said inlet to said fluid pump, second passage means for conducting fluid from said inlet to said fluid motor, and shiftable valve means fluidly communicable with said inlet and said first and second passage means and selectively movable to positively prevent fluid flow between said inlet and first passage means while permitting fluid flow between said inlet and second passage means or to positively prevent fluid flow between said inlet and second passage means while permitting fluid flow between said inlet and first passage means.

2. Hydraulic pressure booster apparatus, comprising a fluid motor, a fluid pump operatively

connected to said motor to be actuated thereby, means providing an inlet for fluid to be supplied to said fluid motor and fluid pump, first passage means for conducting fluid from said inlet to said fluid pump, second passage means for conducting fluid from said inlet to said fluid motor, and shiftable valve means fluidly communicable with said inlet and said first and second passage means and selectively movable to positively prevent fluid flow between said inlet and first passage means while permitting fluid flow between said inlet and second passage means or to positively prevent fluid flow between said inlet and second passage means while permitting fluid flow between said inlet and first passage means, the pressure actuatable area of said fluid motor being greater than the pressure actuatable area of said fluid pump.

3. Hydraulic pressure booster apparatus, comprising a fluid motor, a fluid pump operatively connected to said motor to be actuated thereby, means providing an inlet for fluid to be supplied to said fluid motor and fluid pump, first passage means for conducting fluid from said inlet to said fluid pump, said first passage means constituting both the inlet and outlet for said fluid pump, second passage means for conducting fluid from said inlet to said fluid motor, and shiftable valve means fluidly communicable with said inlet and said first and second passage means and selectively movable to positively prevent fluid flow between said inlet and first passage means while permitting fluid flow between said inlet and second passage means or to positively prevent fluid flow between said inlet and second passage means while permitting fluid flow between said inlet and first passage means.

4. Hydraulic pressure booster apparatus, comprising a body having an inlet passage and an outlet passage, a cylinder on said body and having a portion spaced from said body to form an annular cylinder space, a piston movable longitudinally in said cylinder space and dividing said space into a fluid motor portion and a fluid pump portion communicating with said outlet passage, passage means for conducting fluid from said inlet passage to said fluid motor portion, and shiftable valve means operable to conduct fluid selectively between said inlet and outlet passages or between said inlet passage and passage means.

5. Hydraulic pressure booster apparatus, comprising a body having an inlet passage and an outlet passage, a cylinder on said body and having a portion spaced from said body to form an annular cylinder space, a piston movable longitudinally in said cylinder space and dividing said space into a fluid motor portion and a fluid pump portion communicating with said outlet passage, passage means for conducting fluid from said inlet passage to said fluid motor portion, and shiftable valve means operable to conduct fluid selectively between said inlet and outlet passages or between said inlet passage and passage means, said piston having an area subject to the pressure of fluid in said fluid motor portion which is greater than the area of said piston for imposing pressure on the fluid in said fluid pump portion.

6. Hydraulic pressure booster apparatus, comprising a body having an inlet passage and an outlet passage, a cylinder on said body and having a portion spaced from said body to form an annular cylinder space, a piston movable longitudinally in said cylinder space and dividing said space into a fluid motor portion and a fluid pump portion communicating with said outlet passage,

passage means for conducting fluid from said inlet passage to said fluid motor portion, shiftable valve means operable to conduct fluid selectively between said inlet and outlet passages or between said inlet passage and passage means, and means for bleeding fluid from said passage means when said valve member has been shifted to a position conducting fluid between said inlet and outlet passages.

10. Hydraulic pressure booster apparatus, comprising a body having an inlet passage and an outlet passage, a cylinder on said body and having a portion spaced from said body to form an annular cylinder space, a piston movable longitudinally in said cylinder space and having a head dividing said space into a fluid motor portion and a fluid pump portion communicating with said outlet passage, said piston having a skirt secured to said head and slidable along said cylinder and body, the pressure actuatable area of said piston head on the skirt side of the piston being less than the pressure actuatable area of the other side of said piston head subject to the pressure of fluid in said fluid motor portion, passage means for conducting fluid from said inlet passage to said fluid motor portion, and shiftable valve means operable to conduct fluid selectively between said inlet and outlet passages or between said inlet passage and passage means.

20. Hydraulic pressure booster apparatus, comprising a body having an inlet passage and an outlet passage, a cylinder slidable on said body and having a portion spaced from said body to form an annular cylinder space, a piston movable longitudinally in said cylinder space and dividing said space into a fluid motor portion and a fluid pump portion communicating with said outlet passage, passage means for conducting fluid from said inlet passage to said fluid motor portion, valve means in said cylinder operable to conduct fluid selectively between said inlet and outlet passages or between said inlet passage and passage means, and means for shifting said cylinder longitudinally with respect to said body to dispose said valve means in such selective positions.

30. Hydraulic pressure booster apparatus, comprising a body having an inlet passage and an outlet passage, a cylinder slidable on said body and having a portion spaced from said body to form an annular cylinder space, a piston movable longitudinally in said cylinder space and dividing said space into a fluid motor portion and a fluid pump portion communicating with said outlet passage, passage means for conducting fluid from said inlet passage to said fluid motor portion, valve means in said cylinder operable to conduct fluid selectively between said inlet and outlet passages or between said inlet passage and passage means, and coengaging cam means on said body and cylinder for shifting said cylinder longitudinally with respect to said body, upon relative rotation between said cylinder and body, to dispose said valve means in such selective positions.

40. Hydraulic pressure booster apparatus, comprising a body having an inlet passage and an outlet passage, a cylinder slidable on said body and having a portion spaced from said body to form an annular cylinder space, a piston movable longitudinally in said cylinder space and having a head dividing said space into a fluid motor portion and a fluid pump portion communicating with said outlet passage, said piston having a skirt secured to said head and slidable along said cylinder and body, the pressure actuatable area

11

of said piston head on the skirt side of the piston being less than the pressure actuatable area of the other side of said piston head subject to the pressure of fluid in said fluid motor portion, passage means for conducting fluid from said inlet passage to said fluid motor portion, valve means in said cylinder operable to conduct fluid selectively between said inlet and outlet passages or between said inlet passage and passage means, and means for shifting said cylinder longitudinally with respect to said body to dispose said valve means in said selective positions.

11. Hydraulic pressure booster apparatus, comprising a body having an inlet passage and an outlet passage, a cylinder on said body and having a portion spaced from said body to form an annular cylinder space, a piston movable longitudinally in said cylinder space and dividing said space into a fluid motor portion and a fluid pump portion communicating with said outlet passage, passage means for conducting fluid from said inlet passage to said fluid motor portion, shiftable valve means operable to conduct fluid selectively between said inlet and outlet passages or between said inlet passage and passage means, longitudinally spaced sealing elements between said piston and body on the pump portion side of said piston, and means providing a fluid passage between said motor portion and the region between said sealing elements to subject said elements to the pressure of fluid in said motor portion.

12. Hydraulic pressure booster apparatus, comprising a body having an inlet passage and an outlet passage, a cylinder on said body and having a portion spaced from said body to form an annular cylinder space, a piston movable longitudinally in said cylinder space and dividing said space into a fluid motor portion and a fluid pump portion communicating with said outlet passage, passage means for conducting fluid from said inlet passage to said fluid motor portion, shiftable valve means operable to conduct fluid selectively between said inlet and outlet passages or between said inlet passage and passage means, longitudinally spaced sealing elements between said piston and body on the pump portion side of said piston, and means for conducting fluid from said inlet passage to the region between said sealing elements to subject said elements to the pressure of fluid in said inlet passage.

13. Hydraulic pressure booster apparatus, comprising a body having an inlet passage and an outlet passage, a cylinder on said body and having a portion spaced from said body to form an annular cylinder space, a piston movable longitudinally in said cylinder space and dividing said space into a fluid motor portion and a fluid pump portion communicating with said outlet passage, passage means for conducting fluid from said inlet passage to said fluid motor portion, shiftable valve means operable to conduct fluid selectively between said inlet and outlet passages or between said inlet passage and passage means, longitudinally spaced sealing elements between said piston and body on the pump portion side of said piston, and means providing a fluid passage in said body between said motor portion and the region between said sealing elements to subject said elements to the pressure of fluid in said motor portion.

14. Hydraulic pressure booster apparatus, comprising a body having an inlet passage and an outlet passage, a cylinder slidable on said body and having a portion spaced from said body to form an annular cylinder space, a piston mov-

12

able longitudinally in said cylinder space and dividing said space into a fluid motor portion and a fluid pump portion communicating with said outlet passage, passage means for conducting fluid from said inlet passage to said fluid motor portion, valve means in said cylinder operable to conduct fluid selectively between said inlet and outlet passages or between said inlet passage and passage means, means for shifting said cylinder longitudinally with respect to said body to dispose said valve means in such selective positions, and means for bleeding fluid from said passage means when said cylinder has been shifted to place said valve means in a position establishing communication between said inlet and outlet passages.

15. Hydraulic pressure booster apparatus, comprising a body having an inlet passage and an outlet passage, a cylinder on said body and having a portion spaced from said body to form an annular cylinder space, a piston movable longitudinally in said cylinder space and having a head dividing said space into a fluid motor portion and a fluid pump portion communicating with said outlet passage, said piston having a skirt secured to said head and slidable along said cylinder and body, the pressure actuatable area of said piston head on the skirt side of the piston being less than the pressure actuatable area of the other side of said piston head subject to the pressure of fluid in said fluid motor portion, passage means for conducting fluid from said inlet passage to said fluid motor portion, shiftable valve means operable to conduct fluid selectively between said inlet and outlet passages or between said inlet passage and passage means, longitudinally spaced sealing elements between said body and skirt, and means for conducting fluid from said inlet passage to the region between said sealing elements to subject said elements to the pressure of fluid in said inlet passage.

16. Hydraulic pressure booster apparatus, comprising a body having an inlet passage and an outlet passage, a cylinder slidable on said body and having a portion spaced from said body to form an annular cylinder space, a piston movable longitudinally in said cylinder space and dividing said space into a fluid motor portion and a fluid pump portion communicating with said outlet passage, passage means for conducting fluid from said inlet passage to said fluid motor portion, valve means in said cylinder operable to conduct fluid selectively between said inlet and outlet passages or between said inlet passage and passage means, means for shifting said cylinder longitudinally with respect to said body to dispose said valve means in such selective positions, longitudinally spaced sealing elements between said piston and body on the pump portion side of said piston, and means for conducting fluid from said inlet passage to the region between said sealing elements to subject said elements to the pressure of fluid in said inlet passage.

17. Hydraulic pressure booster apparatus, comprising a fluid motor, a fluid pump operatively connected to said motor to be actuated thereby, means providing an inlet for fluid to be supplied to said fluid motor and fluid pump, first passage means for conducting fluid from said inlet to said fluid pump, second passage means for conducting fluid from said inlet to said fluid motor, third passage means for bleeding fluid from said second passage means, and shiftable valve means fluidly communicable with said inlet and said first, second and third passage means

13

and selectively movable to place said second and third passage means in communication while positively preventing fluid flow between said inlet and second passage means and while permitting fluid flow between said inlet and first passage means or to permit fluid flow between said inlet and second passage means while preventing fluid flow between said inlet and first passage means and between said second passage means and third passage means.

18. Hydraulic pressure booster apparatus, comprising a fluid motor, a fluid pump operatively connected to said motor to be actuated thereby, means providing an inlet for fluid to be supplied to said fluid motor and fluid pump, first passage means for conducting fluid from said inlet to said fluid pump, second passage means for conducting fluid from said inlet to said fluid mo-

14

tor, and a single valve control member fluidly communicable with said inlet and said first and second passage means and movable as a unit to positively prevent fluid flow between said inlet and first passage means while permitting fluid flow between said inlet and second passage means or to positively prevent fluid flow between said inlet and second passage means while permitting fluid flow between said inlet and first passage means.
